(57) CLAIM

We claim the ornamental design for a smoking pipe, as shown and described.

DESCRIPTION

FIG. 1 is an isometric view of a smoking pipe in accordance with the present disclosure;

FIG. 2 is a front view of the smoking pipe of FIG. 1;

FIG. 3 is a rear view of the smoking pipe of FIG. 1;

FIG. 4 is a left view of the smoking pipe of FIG. 1;

FIG. 5 is a right view of the smoking pipe of FIG. 1;

FIG. 6 is a top view of the smoking pipe of FIG. 1; and,

FIG. 7 is a bottom view of the smoking pipe of FIG. 1.

The features shown in broken lines in the figures form no part of the claimed design.

1 Claim, 7 Drawing Sheets(56)
